UNITED STATES PATENT OFFICE.

CLAUS J. WERNER CLASEN, OF DAVENPORT, IOWA, ASSIGNOR, BY MESNE ASSIGNMENTS, TO THE BETTENDORF COMPANY, OF BETTENDORF, IOWA, A CORPORATION OF IOWA.

HOPPER-BOTTOM DUMP-CAR.

1,071,141.

Specification of Letters Patent. Patented Aug. 26, 1913.

Application filed June 10, 1912. Serial No. 702,643.

To all whom it may concern:

Be it known that I, CLAUS J. WERNER CLASEN, a citizen of the United States of America, and resident of Davenport, Scott county, Iowa, have invented a certain new and useful Improvement in Hopper-Bottom Dump-Cars, of which the following is a specification.

My invention relates to improvements in dump cars of the hopper bottom type, wherein the hoppers are arranged on each side of the longitudinal center of the car. Usually these hoppers are formed by the swinging drop doors when in their closed position. My invention, however, contemplates a series of fixed hoppers arranged on each side of the longitudinal center of the car and transversely thereto—the object being to convert the entire floor area into a multiplicity of "scoop like" hoppers with discharge openings, whereby materials can be loaded over the entire floor surface and yet be automatically discharged; whereas, at present, the loading and discharging is confined principally to that portion of the floor area located between the body bolsters of the car body, thus greatly reducing its carrying capacity. When the entire floor, including that portion between the body bolsters and the ends of the car, is formed of drop doors, the car body is soon twisted out of shape due to the absence of diagonal bracing such as would be afforded by a solid floor and it is therefore the general practice to provide discharge openings or hoppers between the trucks only, leaving the remaining portion of the floor solid to insure proper strength to the structure as a whole. It then becomes necessary to partition off those portions of the car, thereby reducing its carrying capacity or permit the ends to become filled and then, on emptying the car, manually remove that portion of the load. The object of my invention is to not only provide automatically dischargeable hoppers throughout and make the entire floor area available for load carrying purposes, but also to produce strength and stiffness to the entire structure to an extent even greater than that afforded by the ordinary solid floor. These and other objects, which will hereinafter appear, I attain by the structure illustrated in the accompanying drawings, in which—

Figure 1 is a vertical cross section of a gondola car through the center sill and hoppers, taken on line A. B. of Fig. 3 looking to the right or toward the needle beam. Fig. 2 is a similar view looking to the left or toward the body bolster. Fig. 3 is a plan view of one end of a gondola car showing one type of hopper on one side of the longitudinal center and another type on the other side. Fig. 4 is a side elevation of the same portion of a gondola as shown in Fig. 3 and shows an end view of both styles of hoppers. Fig. 5 is a perspective view of a hopper having a restricted discharge opening. Fig. 6 is a perspective view of a hopper with an unrestricted opening.

Similar numerals refer to similar parts throughout the several views.

The center sill 2, body bolster 3, truck bolster 4, end sill 5, needle beam 6, side walls 7, stakes 8 and end walls 9, form the underframe and sides of the car and are of usual construction for cars of this kind. Instead of a solid or stationary floor covering the entire area of the car bottom, or a floor made up of drop doors in that portion between body bolsters, and solid or stationary floor sections between the bolsters and ends of car, I provide a floor, extending over the entire bottom from end to end of car, made up of the "scoop like" hoppers 10, arranged in two rows, one on each side of the longitudinal center of the car, each hopper occupying the entire space between adjacent transverse members of the underframe. The spaces between the bolsters 3 and end sills 5 also being occupied by these hoppers and not covered by a fixed floor plate lying flat as is the usual custom in gondolas, or by the long slope sheet generally employed in center dump ore cars or cars of that type. Not only is the rigidity of the car thus assured and the entire floor area capable of being dumped, but the carrying capacity of the car is also greatly increased over that of the drop bottom car with sides of equal height. And again as the carrying capacity of the hoppers themselves represents a large percentage of the entire capacity, the center of gravity of the entire loaded car, as a unit, is greatly and beneficially lowered. These hoppers 10 are preferably formed of two sheets pressed

into proper form as shown in Fig. 5 or can be made from a single sheet as shown in Fig. 6. In the preferred form, one sheet forms the bottom and sides of the "scoop like" hopper and the other forms the outer end 11 which is provided with discharge opening 12. The upper marginal edges 13 of the sides of the hoppers extend perpendicularly in order to contact the vertical webs of the transverse members to which they are riveted as shown at 14, while the rear or lip end 15 of the hoppers extend horizontally, fitting in under and up against the under surface 16 of the eye beam flange 17 forming the center sill 2, to which they are securely riveted. As shown in Fig. 5 the discharge end of the hopper, in its preferred form consists of the flanged plate 11 provided with the flanged opening 12 and the outwardly extending flange 17. This plate is riveted to the downwardly extending flange 17a of the hopper. The flange 17 is riveted to the car sides as shown at 18.

Extending the entire length of the car 25 on each side thereof in the vicinity of the upper part of the hopper openings, is the combined hinge and door lock operating shaft 19. This shaft is supported at its ends in a suitable bearing (not shown) 30 located in the end sill 5, and also by the hangers 20. If hoppers with full openings are employed this shaft is located a trifle higher up and supported by the shorter bearings 21. The doors 22 are swingingly 35 mounted on this shaft by the hinge castings 23. Door latches 24, which are pivotally secured to the doors and which normally rest back of the hasps 25 when the doors are in closed position, are operatively connected to the hinge shaft 19 by the chains 26. It is thus seen that by revolving this hinge shaft by any suitable means at the end of the car, all the doors on one side of the car can be unlocked and permitted to swing 40 open as shown by the door in dotted lines 45 in Fig. 1. Instead of making the shaft continuous from end to end of car it can be divided at the center, each half being operated independently from each end of the 50 car and thereby one half of the doors opened at a time if found desirable—a situation frequently arising in practice.

I am aware that hopper bottom cars have been made wherein the hoppers extended 55 over the entire floor area, but these hoppers were of that type in which the load was discharged straight down between the rails by the use of swinging doors lying flat or horizontal, in the bottom of the hoppers, 60 when in closed position. Thus the floor proper was made up of a large number of articulated parts, offering little or no resistance to the racking and twisting strains to which dump cars are subjected. This 65 is also true, to an even greater extent, in

that type of dump cars in which the hopper sides or bottom are made up of movable floor sections, or of the swinging doors themselves.

In my improved construction it is seen 70 that the hoppers are complete in themselves and when securely riveted to place, form a solid, continuous rigid floor, covering the entire area of the bottom of the car. The doors being hung in practically a vertical position contribute but little to or detract 75 from this rigidity.

What I claim as new is—

1. A hopper bottom car, consisting of a longitudinally extending center sill and side walls, transverse members including end sills, body bolsters, needle beams and end walls; side-delivery chute-like hoppers filling all the spaces formed by the intersection of the longitudinal and transverse members, and in their greatest portion depressed below the plane thereof. 80

2. A hopper bottom car, the entire horizontal area of which consists of side-delivery chute-like individual hoppers, said hoppers being divide in two longitudinal side-by-side series extending from end to end of the car body between the cross-members, the discharge end of said hoppers being depressed below the plane of the car bed 95 or frame. 90

3. A hopper bottom car, intersecting longitudinal and transverse floor framing members, one-piece chute-like hoppers, each rigidly secured to the adjacent intersecting 100 members along their upper edges and extending substantially to the level of the top plane of the floor members, and having their discharge ends approximately in the vertical plane of the car sides and depressed 105 below the plane of the said floor members.

4. A hopper bottom car having a floor 110 consisting of framing members and one-piece hoppers rigidly secured thereto, vertically hung doors engaging the discharge end of said hoppers and combined hinge and door lock operating shafts supporting said doors.

5. A hopper bottom car having permanent upright sides, ends and intersecting 115 floor members, integral side-delivery hoppers permanently secured to said floor members in the spaces formed by said intersections and extending substantially to the level of the top plane of said floor beams. 120

6. A hopper bottom car having permanent upright sides, ends and intersecting floor members, integral side-delivery hoppers permanently secured to said floor members in the spaces formed by said intersections, vertically hung doors engaging the discharge end of said hoppers, and combined hinge and door lock operating shafts supporting said doors. 125

7. A hopper bottom car having upright 130

sides, ends, and intersecting floor members, floor sheets extending substantially over the entire bottom area permanently secured to the floor members near the top plane thereof, and depressed between the intersecting floor members forming chute-like side-delivery hoppers.

Signed by me at Davenport, Iowa, this 6th day of June, 1912.

CLAUS J. WERNER CLASEN.
